UNITED STATES PATENT OFFICE.

CHARLES BOOZ, OF BUFFALO, NEW YORK, ASSIGNOR TO HENRY M. BIRGE,
OF SAME PLACE.

DESIGN FOR WALL-PAPER.

SPECIFICATION forming part of Design No. 26,087, dated September 22, 1896.

Application filed August 5, 1896. Serial No. 601,822. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of an arrangement of ornamental panels formed of ornamental scrolls, with palm-like ornaments in the center of said panels and small palm-like ornaments on the top of said panels, as represented in 15 the accompanying drawing. Light ornamental scrolls diverge right and left from the small palm-like ornaments around said panels and form part of the design.

The border of said design is also formed of similar ornamental panels, with palm-like 20 ornaments in the center and ornamental scrolls diverging right and left from the base of said panels, as shown in the drawing.

What I claim is—

1. The design for wall-paper herein shown 25 and described.

2. In the design for wall-paper the border herein shown and described.

Witness my hand this 1st day of August, 1896.

CHARLES BOOZ.

Witnesses:

E. R. DEAN,
KATHRYN ELMORE.
